[57] CLAIM

The ornamental design for a cutting attachment for paper roll holder or similar article, as shown and described.

DESCRIPTION

FIG. 1 is a perspective view of a cutting attachment for paper roll holder or similar article showing our new design; and

FIG. 2 is a view similar to FIG. 1 but slightly rotated counterclockwise as seen from above and taken from a higher angle.

The device is identical in appearance to FIGS. 1 and 2 for each of the other three positions thereof rotated through increments of 90°.

FIG. 1

FIG. 2
